UNITED STATES PATENT OFFICE.

JOHN HENRY NELSON, OF NEW CASTLE, PENNSYLVANIA.

CLOTHES-HANGER CABINET.

1,345,624.

Specification of Letters Patent.

Patented July 6, 1920.

Application filed August 4, 1919. Serial No. 315,254.

To all whom it may concern:

Be it known that I, JOHN HENRY NELSON, a citizen of the United States, residing at New Castle, in the county of Lawrence and State of Pennsylvania, have invented certain new and useful Improvements in Clothes-Hanger Cabinets, and I do declare the following to be a full, clear, and exact description of the invention, such as will enable others skilled in the art to which it appertains to make and use the same.

This invention relates to clothes-hangers, also to cabinets, and it relates more specifically to what might be termed a clothes-hanger cabinet.

One object of this invention is to generally improve upon devices of this character by providing an improved foldable clothes-hanger that is exceedingly strong, durable, rigid and compact, consistent with lightness and low cost of manufacture, and in which the supporting levers are thoroughly protected from dust and are very efficiently supported by a series of superposed shelves which alternate with one or more superposed series of supporting bars.

Other objects and advantages may become apparent to persons who read the following details of description in connection with the accompanying drawings in which:—

Figure 1 is a front view of a device constructed in accordance with the present invention, the door being omitted.

Fig. 2 is a horizontal sectional view, the section being taken between two of the shelves.

Fig. 3 is a transverse vertical sectional view, the section being taken along the line 3—3 of Figs. 1 and 2.

Fig. 4 is a view similar to Fig. 2, but illustrating a somewhat modified form of the invention.

Fig. 5 is a view similar to Fig. 3, but illustrating the modified form shown in Fig. 4, the section being taken along the line 5—5 of Fig. 4.

Fig. 6 is a view similar to Fig. 4, but portions of the supporting bars being broken off, and the same being shown in the extended or clothes-supporting position.

Referring to these drawings in detail, in which similar reference characters correspond with similar parts throughout the several views, the device illustrated in Figs. 1, 2 and 3 comprises a series of superposed shelves or plates 1, 2 and 3, the shelf 1 con-

stituting the top or cover plate of a box or casing and the shelf 2 constituting the bottom or floor plate of the box or casing. The shelves 3 constitute partition-plates. 60 End walls 4 are united with the shelves or plates 1 and 2 so as to secure them in fixed position to one another, a rear wall 5 closes the rear side of the casing, and a door 6 closes the front of the casing. Corner 65 brackets 7 extend around the corners of the cabinet and are secured thereto by any appropriate means so as to add strength and rigidity to the structure. The end walls 4 are preferably formed with horizontal 70 grooves 8 which are spaced equi-distant from one another, and the ends of the shelves 3 are fitted in these grooves so that the spaces between the shelves are equal in vertical extent. The door 6 is preferably hinged at 75 9 and adapted to swing downward and depend from the lower shelf 2 when the box is open for use, and any appropriate form of lock or latch 10 may be provided on the upper shelf 1 for engaging with the door 6 80 and holding it closed.

Two series of supporting bars 11 are arranged in alternate relation with the shelves 1, 2 and 3; that is, each bar of each series has one end seated between two adjacent 85 shelves and has its upper and lower surfaces touching the respective lower and upper surfaces of contiguous shelves, and a pivot-rod 12 extends through the relatively thick ends of the bars 11 and through the 90 entire series of shelves so as to pivotally connect these bars to the shelves in such relation that the shelf above each bar coacts with the shelf below and with the pivot-rod for supporting the respective bars against 95 sagging or being depressed from the horizontal position. For this purpose, the pivot bearing of each bar 11, through which the pivot-rod 12 extends, is located at a distance from the end of the bar sufficient to provide 100 a short arm 11' which bears upward against the superjacent shelf while the long arm 11² bears down on the subjacent shelf. Moreover, it will be seen that the pivot-rod 12 is supported against bending in consequence 105 of its engagement with each of the shelves, which increases the efficiency of each rod 12 as a support for the bars 11. These bars are preferably of the same vertical extent or height throughout their length, but are tapered from their inner ends to their outer ends with regard to their horizontal extent 110

UNITED STATES PATENT OFFICE.

JOHN J. O'DONNELL, OF MIDDLETON, CONNECTICUT.

BAKE-PAN.

1,345,625.

Specification of Letters Patent.

Patented July 6, 1920.

Application filed June 4, 1919. Serial No. 201,787.

To all whom it may concern:

Be it known that I, JOHN J. O'DONNELL, a citizen of the United States, residing at Middletown, in the county of Middlesex and 5 State of Connecticut, have invented certain new and useful Improvements in Bake-Pans, of which the following is a specification.

This invention relates to domestic cooking utensils, and more especially to pans; 10 and the object of the same is to produce a bake pan in which the cake will not stick as it so frequently does.

This object is carried out by the construction of the pan which permits one or more 15 of its upright panels to fall or to be turned down to a horizontal, so that a knife can be inserted under the cake or other cooked product and the same scraped off the bottom of the pan. Before turning down the 20 upright panels, the knife can be inserted to separate the cake therefrom. As the pans are now made, it is quite impossible to insert a knife under the cake or the like, and my invention obviously avoids the difficulty. In 25 the preferred form of my invention, the several panels let down, as they are hinged to the edges of the bottom of the pan and means are provided to hold them upright until they are to be purposely let down. De- 30 tails are set forth below, and attention is drawn to the drawings, wherein—

Figure 1 is a side elevation,

Fig. 2 a longitudinal section,

Fig. 3 a cross section and

35 Fig. 4 a detail plan view of one corner.

The bottom 1 is preferably flat, being surrounded by a small flange 2 which is bent obliquely downward from the plane of the bottom as seen in Fig. 3 and formed with 40 knuckles 3. With a pan square or rectangular in contour, there are two sides and two ends, but I do not wish to be limited to the shape of the pan and therefore I refer to the upright elements as panels. Each has 45 a body 4 which is preferably flat and its lower edge flanged outward as at 5 and formed with knuckles 6 alternating with those numbered 3 on the bottom and pintle pins 7 are run through the aligned knuckles 50 to convert them into hinges. The upper edge of each panel may be beaded as indicated at 8. It is to be understood that there may be more than four panels if desired and that they may rise vertically or otherwise. 55 I show them as inclined slightly outward,

as is the usual construction of bake pans, and therefore their ends will come together on meeting lines 10 (Fig. 4) when their flanges 5 contact with the flanges 2 on the bottom 1. On said ends I provide outwardly 60 projecting lips which may or may not extend the complete height of the panels, although they may rise to the upper edges thereof and the beads 8 may have to terminate slightly short of the panels as seen 65 in Fig. 4 it being noted that one lip 11 of each pair has a bead 11' on its outer edge. These contacting lips 11 are connected by clips indicated at 12. A clip 12 is riveted, as at 12', upon one lip 11 of each pair, as 70 shown in Fig. 2. As the clip is substantially U-shaped and is of highly resilient material it may be snapped around the lips and over the bead 11', thus holding the lips together. Now when the pan is set up as seen in the 75 drawings and filled with dough it is placed in the oven and baking takes place. When it is removed, a knife blade is passed down inside the panels and the sides of the cake or loaf separated therefrom. Then the clips 80 12 are sprung from engagement with some of the lips 11 and the panels are let down, turning easily on their hinges as will be clear. In this condition they lie substantially horizontal or in about the same plane 85 as the bottom panel 1, and now a knife can be run under the cake or loaf, so as to separate it from the bottom. Thus sticking is avoided and it will be quite easy to wash the pan in its collapsed condition. It will be 90 noted from Fig. 3 that the flanges 2 and the knuckles 3 cause the bottom to be raised somewhat above the plane of the stove top upon which the knuckles rest, and this avoids burning of the cake or loaf. While 95 I have shown all four panels as hinged, this is not absolutely necessary. Again I remark that I do not wish to confine myself to four panels, and in fact they need not be entirely separate from the bottom as some 100 of them may be integral therewith or fastened thereto, and others hinged. The primary object is to permit the insertion of the knife blade over the bottom as described above.

105 The foregoing description and the drawings have reference to what may be considered the preferred form of my invention. It is to be understood that I may make such changes in construction and arrangement 110
